(57) **CLAIM**

The ornamental design for a oval sidemarker lamp, as shown and described.

DESCRIPTION

FIG. 1 is a perspective plan view of a first embodiment of our new oval sidemarker lamp design.

FIG. 2 is a top plan view of a first embodiment of our new oval sidemarker lamp design.

FIG. 3 is a first side elevational view of a first embodiment of our new oval sidemarker lamp design.

FIG. 4 is a second side elevational view of a first embodiment of our new oval sidemarker lamp design.

FIG. 5 is a bottom plan view of a first embodiment of our new oval sidemarker lamp design.

FIG. 6 is a first end elevational view of a first embodiment of our new oval sidemarker lamp design; and,

FIG. 7 is a second end elevational view of a first embodiment of our new oval sidemarker lamp design.

The broken line showing of the connector tips is included for the purpose of illustrating the connector tips and forms no part of the claimed design.
